UNITED STATES PATENT OFFICE.

GEORGE E. MONTAGUE, OF WEST SPRINGFIELD, MASSACHUSETTS.

CAPTIVE AEROPLANE.

Application filed December 7, 1920. Serial No. 429,042.

To all whom it may concern:

Be it known that I, GEORGE E. MONTAGUE, a citizen of the United States of America, and a resident of West Springfield, in the 5 county of Hampden and State of Massachusetts, have invented a new and useful Captive Aeroplane, of which the following is a specification.

My invention relates to improvements in 10 devices which are capable of being raised on or by the action thereon of wind or air currents, and partake more or less of the nature of aeroplanes or similar devices or machines, and resides more especially in a 15 wind- or air-operated device or appliance which is mounted and adapted to rise and fall and swing on a rod, spindle, wire, or other suitable supporting standard or member together with such other features, parts, 20 and members, as may be necessary or desirable in order to render the appliance complete, satisfactory, and serviceable, such as yielding means or a flexible connection whereby the pitch of the lifting planes may 25 be automatically changed to increase or decrease the resistance of the same to the wind or air currents, locking means for said planes, a brake for the propeller, a brake or lock whereby the movable parts on the 30 supporting member may be retarded in their movement or held stationary thereon, a counterweight for said movable parts, and a suspended body or car, any or all of these features, parts, and members, and others as 35 well, being applicable to what may be termed the primary elements of my invention, all as hereinafter set forth.

The primary object of my invention is to 40 produce an appliance which comprises an approximately vertical guide member, and a connected aeroplane element which is capable of rising or being moved upwardly on said member by the action of air currents forced against it, or such action when 45 said aeroplane element is forced through the air, the flight of the aeroplane element being limited, and the descent thereof also being limited, and the aeroplane being guided between the upper and lower limits 50 of movement or the predetermined limits of flight and descent of the same. The aeroplane element is capable, also, of circling about or around the guide member. Thus 55 the aeroplane element is held captive, although free to move vertically within predetermined limits, and to swing horizontally

as on a pivot. The guide member or guide may be stationary, or it may be carried in the hand or on a vehicle.

Another object of my invention is to provide a captive aeroplane, of the character described above, which can be made in various sizes. It may be small enough to be used by a child as a toy, or of a size sufficiently large to hold one or more persons. 60 Moreover, the appliance can be used in various ways, as by being mounted on or attached to an automobile, carried about in the hand, or mounted on or suspended from a building or other fixed support, or by having its supporting member or guide firmly set in the ground or on a fixed base, as when said appliance is made of a size large enough for the accommodation and actual carrying of children or grown people. 65 70 75

Still another object is to afford means in a captive aeroplane, whereby the pitch of the planes thereof is or may be automatically varied or adjusted to meet the variations in the air currents or wind pressure, and thus 80 protect said planes and other parts of the appliance from injury.

Other objects and advantages will appear in the course of the following description.

I attain the objects and secure the advantages of my invention by the means illustrated in the accompanying drawings, in which—

Figure 1 is a side elevation of a captive aeroplane which embodies a practical form 90 of my invention, middle portions of the rods and rope being broken out; Fig. 2, an enlarged, side elevation of the forward portion of the aeroplane element which is illustrated in the preceding view; Fig. 3, an 95 enlarged, top plan of parts of said aeroplane element showing locking means for the forward planes; Fig. 4, an enlarged detail, in partial section, showing the brake or lock by means of which said element may 100 be secured at any point on the supporting member or guide therefor; Fig. 5, a side elevation of an aeroplane element which is provided with a body or car at the bottom; Fig. 6, a side elevation of an aeroplane element having a single forward plane; Fig. 105 7, a front elevation of an aeroplane element which has box planes, and, Fig. 8, an elevation of a supporting member or guide which is designed more especially to be carried in the hand, the central portion thereof being broken out. 110

Similar characters of reference designate similar parts throughout the several views.

As previously intimated, my invention consists of or comprises in each case a supporting member or guide which is usually positioned vertically or approximately so, and an aeroplane element which is provided with means whereby the same may be freely and loosely connected with said guide and rises and falls thereon and circles about the same, such element including, if desired or necessary, certain subsidiary or auxiliary features, of some of which mention has been made and a description in detail will subsequently be given.

The aeroplane element or aeroplane proper, apart from its guide, which is also its keeper, will hereinafter be termed merely aeroplane.

20 The aeroplane in each case consists in part of a suitable framework or frame, one of the more essential members of which is a backbone or its equivalent.

I will first describe in detail the captive aeroplane illustrative in the first four views of the drawings. This captive aeroplane is susceptible of use for carrying children or grown people, provided the same be made sufficiently large and strong, although it, like the other examples shown in connection herewith, is primarily intended to be used as a toy and would then be too small to support any considerable weight.

The captive aeroplane in question consists of a supporting member, rod, or guide 1, and an aeroplane which comprises and includes a body 2, the same being only an imitation, a backbone 3, upper and under, forward, lifting planes 4 connected at their front, longitudinal edges by a series of braces, the intermediate pair of which appear at 5, and connected at their rear, longitudinal edges by a series of braces as 6, a propeller 7 mounted at the front 45 end of a horizontal support 6 which in turn is mounted on said guide, a link 9 and a pin 36 connecting said pair of braces 5 with said support, a staple 10 and an eye-bolt 11 through which said guide passes and by means of which said support 8 said aeroplane is attached to or connected with said guide, and an auxiliary vane, fin, or plane 40 on each side of said backbone, and a rudder 41 rising from said backbone at the rear terminal thereof. In addition to the aforesaid parts and members there is an extension rod 12 mounted on the guide 1, a rope 13, and a weight 14.

In both Figs. 1 and 2 the braces are omitted which if in place would hide the central pair at 5.

The guide 1 may be attached at the bottom to any suitable support, and said guide is provided at the lower terminal with a 65 nut 15 and a washer 16 upon which latter

rests a bumper or shock-absorber in the form of a spiral spring 17. This spring serves as a cushion for the aeroplane when it descends, the eyebolt 11 being then received on top of said spring. There is a similar 70 bumper or shock-absorbing spring 17 at the upper terminal of the guide 1, and this serves to cushion the aeroplane when it ascends, the eye-bolt 10 then contacting with the bottom of said spring. Thus the aeroplane is protected or saved from undue shock or jar. The upper spring 17 bears at the top against one of a pair of nuts 18 which nuts are screwed on the upper terminal of the guide 1. A disk 19 is held in 80 place between the upper nut 18 and a nut 20 above said disk. Guy wires or ropes may be attached to the disk 19 in the event it be necessary or desirable to support or brace the guide 1 at the top. The extension rod 85 12 has a horizontal eye 21 at the base which fits over the upper terminal of the guide 1 and is received between a pair of washers 22 on said terminal, said washers and said eye being held in place by the nut 20, and a nut 90 23 on said guide above the upper washer. Another disk, for additional supporting members for the guide 1, is represented at 95 24 on the upper terminal portion of said guide, whereon it is held securely by means of the nut 23 and a nut 25 on said guide above said disk. Either or both of these disks might be removed to the top of the extension rod 12 if desired.

The extension rod 12 is provided at the 100 top with an angular bracket 26. The horizontal part of the bracket 26 fits over the upper terminal of the rod 12 and is secured thereto by means of a pair of nuts 27 and a pair of washers 28 on said terminal. A pulley-block 29 is supported from the vertical part of the bracket 26. One end of the rope 13 is attached at 30 to the top of the upper plane 4 near the front, longitudinal edge thereof, and said rope passes upwardly through the pulley-block 29 and downwardly to have the weight 14 attached thereto at the free end thereof. The object or purpose of the weight 14 will be presently explained. The rod 12 may be arranged to rotate or swivel 110 on the guide 1.

The staple 10 is attached to the upper plane 4 and projects beyond the front, longitudinal edge thereof, while the eye-bolt 11 is movably connected, by means of plates 31, with the 120 intermediate braces 5. The eye-bolt 11 is bifurcated and passes through the plates 31 which are secured to the front and back sides of said braces 5 just above the bottom plane 4 and adjacent to the front, longitudinal edge of the latter. At the rear end of one of the aforesaid shanks is a nut 32, and a spring 33 encircles said shank between said nut and the rear plate 31.

The vertical opening in the support 8 for 130

the guide 1 is shown at 34 in Fig. 3. There is a transverse slot 35 in the support 8 adjacent to the rear end thereof, and a pin 36 passes through the intermediate braces 5 and said slot. The rear terminal portion of the support 8 passes between the intermediate braces 5. The link 9 has one end pivoted at 37 to the upper terminal of one of the intermediate braces 5, and the other end 10 is pivoted at 38 to the support 8 forward of the position of the opening 34.

The member 2 and the backbone 3 are rigidly attached to the intermediate braces 5.

It will now be seen that the planes 4, with the member 2 and the backbone 3, can oscillate on the pivot 36, under the control of the link 9, so as to change the pitch of said planes, and that the latter will normally be retained by the spring 33 with 20 a downward and rearward inclination, owing to the fact that said spring bears between the nut 32 on the bifurcated eye-bolt 11 which is mounted on the guide 1, and the rear plate 31 which is attached to the 25 intermediate braces 5. The amount of tension with which the planes 4 and attached parts are held by the spring 33 may be varied by adjusting the nut 32 on the shank of the eye-bolt 11 which carries said nut 30 and the spring 33. By screwing the nut 32 farther on to its shank the spring 33 has a greater compression, consequently more force is required to rock the planes 4 upwardly and the aeroplane will not descend 35 on the guide 1 so easily or quickly. By screwing the nut 32 outwardly on its shank the spring 33 has less compression, consequently less force is required to rock the planes 4 upwardly and the aeroplane will 40 descend on the guide 1 more easily and quickly.

The propeller 7 is mounted loosely on a stud or screw 39 which projects from the front end of the support 8, and said propeller is freely revolved by the air currents which come in contact with the same or with which the propeller comes in contact. The propeller performs no function other than to serve as a revolving member.

50 The auxiliary planes 40, which extend laterally from the back bone 3, cooperate to a greater or less extent with the planes 4, while the rudder 41 acts as a steering member to cause the aeroplane to head up into the wind, the aeroplane then swinging about the guide 1.

As the air currents come into contact with the planes 4 and 40 and the rudder 41 the aeroplane is elevated on the guide 1 and rotated thereon rising and falling on said guide and turning about the same in accordance with the variations in the velocity and direction of said currents. As the aeroplane rises and falls on the guide 1 it encounters 65 the bumpers or springs 17, so that no in-

jury is received. In the event the air currents overcome the resistance of the spring 33, the latter yields and the planes 4 and rigidly attached parts swing upwardly and reduce the angle thereof relative to the horizon, whereby danger of breakage is practically eliminated. The planes 4 and rigidly attached parts oscillate on the pivot 36, which moves back and forth in the slot 35, 70 the link 9 controlling such movement. 75

In the event it be desired to lock the planes 4 and rigidly attached parts against oscillatory movement, a wedge 42 may be inserted in the slot 35 in the support 8, either in front of or behind the intermediate braces 80 5, and there held by means of vertical pins 43. If the wedge 42 be placed in front of said braces 5, the parts are locked with the planes 4 in a more nearly horizontal position so that they are less affected by wind, 85 than when said wedge is introduced behind said braces. The wedge 42 has a plurality of holes 44 therein to receive the pins 43 and so provide gradations of adjustment for the planes. 90

If desired, a brake for the propeller 7 may be provided, and also a brake or stop for the aeroplane on the guide 1.

The brake for the propeller 7 consists of an angular lever 45 which is pivoted at 46 to 95 one side of the support 8, and has at its forward end a shoe 47, which shoe is located in position to be thrust into contact with the hub of said propeller, when such shoe is actuated forward by depressing the rear terminal or handle of said lever. A spring 48 extends between the handle of the lever 45 and a suitable point of attachment on the upper plane 4, and a spring 49 extends from said handle downwardly to a suitable point 100 of attachment on one of the intermediate braces 5. The spring 49 is stronger than the spring 48, and normally said first-named spring is disconnected at one end or the other, so that said second-named spring retains the 105 shoe 47 out of engagement with the propeller 7. Upon attaching the spring 49 so that it draws down the handle of the lever 45, the shoe 47 is thrust against the hub of the propeller 7 with sufficient force either to stop 110 the same altogether or to cause it to revolve more slowly. The amount of pressure of the shoe 47 on the propeller hub depends on the strength of the spring 49, of course, and on the amount of tension which is given the 115 same and which may be varied by inserting it in one or another of several holes 50 provided in the brake-lever arm for that purpose. 120

Brake elements, whereby the aeroplane 125 may be locked to the guide 1 or may be caused to move less freely thereon, consist of an angular lever 51 which is fulcrumed on a horizontal pin 52 in the intermediate braces 5 just under the upper plane 4, a shoe 130

53 on the down-turned terminal portion of said lever, and a spring 54. The shoe 53 is in position to engage the guide 1 when the lever 51 is depressed at the rear end and thus 5 rocked on the pin 52. Normally the lever 51 is disposed, with the shoe 53 out of contact with the guide 1, by the spring 54 which is connected at the rear end with a hook 55 on the inside of one of the intermediate 10 braces 5, the front terminal of said spring being connected with the rear terminal of said lever. Upon detaching the spring 54 and pressing down the rear terminal of the lever 51, or pressing down said rear terminal 15 without detaching said spring, the shoe 53 is thrust into contact with the guide 1, the force of such contact depending upon the amount of power exerted on said rear terminal, so that the shoe may act merely as a 20 brake to slow up the action of the aeroplane on the guide 1, or it may serve as a lock to bind said aeroplane so tightly to said guide that there will be no movement of the former on or relative to the latter.

25 The office of the weight 14, acting through the rope 13 on the aeroplane, is to counter-balance and stabilize the latter more or less and assist in raising the same. This counterweight is an auxiliary device that would 30 only be used in the event the aeroplane were to carry a considerable load, as when used for carrying people.

In the event it be desired to suspend the 35 guide 1, rather than to support the same from below, the same may be done by attaching either of the disks 19 or 24 to a suitable overhead support.

In Fig. 5 I show an aeroplane which comprises, with planes, a rudder, and a propeller which are very similar to corresponding elements that have already been described, a backbone 56 to the front end of which a propeller 7 is connected, depending 40 posts or supports 57 and 59, the former being 45 in front of the latter, a brace 82 between said backbone and said support 58, and a body or car 59. The support 57 extends above the backbone 56, and the intermediate plane brace 5, which is the one shown, is pivoted at 50 the top to said support as represented at 6. The support 57 is provided above and below the horizontal plane of the backbone 56 with eye-bolts 61—61 which are the elements that are directly mounted on the guide 1, or on 55 any other standard with which this aeroplane may be connected. A spring 62 has one end connected with the brace 5 below the pivot 60, and the other end connected with the backbone 56 forward of said brace. This 60 spring has a constant tendency to draw the planes 4 downwardly, with the rear, longitudinal edge of the upper plane bearing on the backbone 56, in position to afford the practical maximum resistance to the air currents, but said spring will yield, under too

strong pressure from the wind, so that said planes may swing upwardly and rearwardly on the pivot 60, and thus be relieved from undue strain and protected from liability of breakage. Two series of transverse openings 70 75 63 are provided in the backbone 56 adjacent to the braces 5 and 6, for the purpose of receiving pins by means of which said uprights may be held stationary to give any desired fixed pitch or angle to the planes 4, the pins (not shown) being inserted in openings both in front of and behind either or both of said braces, after the proper or desired adjustment has been made.

The car 59 may be provided at the front 80 end with a propeller 7, the same being loosely mounted on a stud or screw 39 which projects from the forward end of a support 64 carried by said car; and the latter may be provided at the rear end with laterally 85 extending, auxiliary planes 40. In order to enhance the appearance of the car 59 and render the illusion more complete, the same may be provided with wheels 65 to run on the ground, such wheels being connected 90 with arms 66 that are pivoted at 83 to the sides of said car and capable of being turned up to locate said wheels above the bottom of said car, as shown in the drawing.

The Fig. 5 aeroplane might be made large 95 enough to carry passengers and to be used in place of the aeroplane shown in Fig. 1, or the latter might be equipped with the car 59 and its appurtenances. The counterweight may be used in connection with this aeroplane.

The aeroplane illustrated in Fig. 6 is a simple appliance that consists of a backbone 67 to which auxiliary planes 40 and a rudder 41 are attached, a vertical post or 105 support 68 with the intermediate portion of which the forward terminal of said backbone is pivotally connected at 73, the pivot passing through a longitudinal slot 74 in said backbone, a single, forward plane 69 110 which is pivotally connected by a plurality of rings 70 at its forward, longitudinal edge with the upper edge portion of a transverse bar 70 secured to the support at the upper terminal thereof, eye-bolts 61—61, and a 115 spring 72. The support 68 extends above and below the horizontal plane of the backbone 67, and said support has a forwardly-extending rod 84, with a stud or screw 39 in the outer end for a propeller. The eye-bolts 61 extend from the front side of the support 68 to receive the guide on or with 120 which this aeroplane is used. The spring 72 has one end connected with the support 68 below the pivot 73, and the other end connected with the backbone 67 behind the slot 74 therein, a plurality of holes 90 in said backbone being provided for said spring so that the tension of the latter may be varied. The spring is arranged and adapted normally 125 130

to retain the pivot 73 in the rear end of the slot 74, and to yield under excessive pressure of wind on the planes 69 and 40 to relieve such pressure and to prevent damaging the 5 parts, as do corresponding springs in the other examples.

If desired a wedge 75 may be inserted in the slot 74 to retain the pivot 73 in the front end of said slot, or at some intermediate position, so as to decrease permanently or while said wedge is in place the effectiveness 10 of the wind on the planes. The wedge 75 is held in place by pins, one of which is represented at 76, in substantially the same 15 manner as is the wedge 42 held by the pins 43.

In Fig. 7 I illustrate an aeroplane which is in a sense box-shaped, that is to say, the planes are made of sheet metal which is 20 bent to form the planes themselves, and also to form side connections which take the place of the braces 5 and 6 in the other constructions wherein two lifting planes are provided at the forward end of the aeroplane. The forward planes are here represented by the numeral 78. The planes 77 are secured to a central upright 79 which is 25 provided with eye-bolts 61 to serve the same purpose as corresponding eye-bolts in the other appliances. The upright 79 is secured to a backbone 85. A propeller 7 is mounted on a stud 39 which projects forwardly from the upright 79 near the base thereof. In other respects, and more particularly 30 with relation to the rear end of this aeroplane, the construction is similar to the others.

The guide 1 illustrated in Fig. 8 is provided at the bottom with a handle 80, and 40 at the top with a ring 81. The handle is designed to be carried in the hand of a child or person using one of these appliances as a toy, while the ring 81 is provided for the purpose of suspending the guide 45 from a suitable support should it be desired to do so. The ring 81 also serves as a stop for the upper bumper or spring 17. This guide must be thrust down through the eye-bolts or equivalent members of the aeroplane, before the bottom spring 17 is placed 50 on said guide and the handle 80 is attached thereto.

Any of the modified aeroplanes hereinbefore described may be used or mounted on 55 any suitable guide 1, and the same operates thereon in a manner similar to that described in connection with the aeroplane shown in the first view, that is to say, the aeroplane in any case is actuated upwardly 60 by the wind or air currents acting against the under sides of the lifting planes, and when the current weakens said aeroplane descends, and the aeroplane circles about the guide as motion is imparted to the former 65 by the action of the air currents or the

wind on the rudder. The shock-absorbers or springs 17 are used in practically every case for the purpose of reducing to the minimum shock and jar and the liability of injury or breakage.

Although I have herein shown and described a number of different applications of my invention, it is to be understood that I have by no means exhausted the possible variations, wherefore I do not desire to be 70 limited to the exact constructions herein shown and described, but seek to cover all modifications and changes which fall within the scope of my claims.

What I claim as my invention, and desire 80 to secure by Letters Patent, is—

1. The combination, in a captive aeroplane, with a rod provided with a handle at the bottom and with projecting means at the top, of an aeroplane consisting in part of a 85 lifting air plane, and in part of connecting means between said plane and the aeroplane body to enable the plane automatically to move upwardly and downwardly, relative to said body, under the action on said plane of 90 the air currents with which the same comes in contact, whereby the angle of the plane to said body is changed, and provided with means for loosely attaching said aeroplane at one terminal to said rod between said handle and said projection, the construction and arrangement of parts being such that the aeroplane rises and falls and swings in 95 horizontal planes at said terminal on said rod.

2. The combination, in a captive aeroplane, with a supporting member, of an aeroplane slidably connected with said supporting member, and consisting in part of a lifting air plane which causes said aeroplane 105 to move upwardly and downwardly, on said supporting member, under the action thereon of the air currents with which said plane comes in contact, and provided with means whereby the angle of said plane to said supporting member may change.

3. The combination, in a captive aeroplane, with a supporting member, of an aeroplane slidably and rotatably connected with said supporting member, and consisting 115 in part of a lifting air plane which causes said aeroplane to move upwardly and downwardly, on said supporting member under the action thereon of the air currents with which said plane comes in contact, and provided with means whereby the angle of said plane to said supporting member may change.

4. The combination, in a captive aeroplane, with a supporting member, of an 120 aeroplane slidably connected with said supporting member, and consisting in part of a lifting air plane which causes said aeroplane to move upwardly and downwardly, on said 125 supporting member under the action thereon of the air currents with which said plane comes in contact, and provided with means whereby the angle of said plane to said supporting member may change.

of the air currents with which said plane comes in contact, and provided with means whereby the angle of said plane to said supporting member may be changed and fixed.

5. The combination, in a captive aeroplane, with a supporting member, of an aeroplane slidingly and rotatably connected with said supporting member, and consisting in part of a lifting air plane which causes said aeroplane to move upwardly and downwardly, on said supporting member, under the action thereon of the air currents with which said plane comes in contact, and provided with means whereby the angle of said plane to said supporting member may be changed and fixed.

6. The combination, in a captive aeroplane, with a supporting member, of an aeroplane slidingly connected at one terminal with said supporting member, and consisting in part of a lifting air plane which moves upwardly and downwardly under the action thereon of the air currents with which said plane comes in contact, the construction and arrangement of parts being such that the aeroplane rises and falls at said terminal on said supporting member, and yielding means to limit both the upward and downward movement of said aeroplane on said supporting member.

7. The combination, in a captive aeroplane, with a rod provided with upper and under projecting members, and spiral springs arranged on said rod between said projecting members, of an aeroplane consisting in part of a lifting air plane which moves upwardly and downwardly under the action thereon of the air currents with which said plane comes in contact, and provided at one terminal with means for loosely attaching said aeroplane to said rod between said springs, the construction and arrangement of parts being such that the aeroplane rises and falls and swings in horizontal planes at said terminal on said rod, and is received by said springs at the ends of its vertical travel.

8. The combination, in a captive aeroplane, with a supporting member, of an aeroplane slidingly connected at one terminal with said supporting member, and consisting in part of a lifting air plane which causes said aeroplane to move upwardly and downwardly, on said supporting member, under the action thereon of the air currents with which said plane comes in contact, and provided with means whereby the angle of said plane to said supporting member may change, and an air rudder carried by said aeroplane at the opposite terminal.

9. The combination, in a captive aeroplane, with a supporting member, of an aeroplane slidingly connected at one terminal with said supporting member, and consisting in part of a lifting air plane which causes said aeroplane to move upwardly and down-

wardly, on said supporting member, under the action thereon of the air currents with which said plane comes in contact, and provided with means whereby the angle of said plane to said supporting member may change, and an air propeller carried by said aeroplane at said terminal.

10. The combination, in a captive aeroplane, with a supporting member, of an aeroplane slidingly connected at one terminal with said supporting member, and consisting in part of a lifting air plane which causes said aeroplane to move upwardly and downwardly, on said supporting member, under the action thereon of the air currents with which said plane comes in contact, and provided with means whereby the angle of said plane to said supporting member may change, an air propeller carried by said aeroplane at the opposite terminal, and a friction brake for said propeller.

11. The combination, in a captive aeroplane, with a supporting member, of an aeroplane movably connected with said supporting member, and consisting in part of a lifting air plane which moves upwardly and downwardly under the action thereon of the air currents with which said plane comes in contact, and means to engage said supporting member and check the movement of said aeroplane between the limits of its up and down travel.

12. The combination, in a captive aeroplane, with a supporting member, of an aeroplane movably connected with said supporting member, and consisting in part of a lifting air plane which moves upwardly and downwardly under the action thereon of the air currents with which said plane comes in contact, said aeroplane being provided with a friction brake to engage said supporting member and check the aeroplane in its movement relative to said supporting member.

13. The combination, in a captive aeroplane, with a supporting member, of an aeroplane, movably connected with said supporting member, and comprising a lifting air plane, and a flexible jointed connection whereby the angle of said plane to said supporting member may be automatically varied.

14. The combination, in a captive aeroplane, with a supporting member, of an aeroplane movably connected with said supporting member, and comprising a lifting air plane, and a flexible jointed connection whereby the angle of said plane to said supporting member may be automatically varied, and locking means for said connection.

15. The combination, in a captive aeroplane, with a supporting member, and a superimposed rod provided with a pulley, of an aeroplane movably connected with said supporting member, and consisting in part of a lifting air plane, a rope passing over

said pulley and having one end attached to said aeroplane, and a weight attached to the other end of said rope.

16. The combination, in a captive aeroplane, with a supporting member for an aeroplane, of an aeroplane movably connected adjacent to one terminal of the aeroplane with said supporting member, said aeroplane consisting in part of a lifting air plane, and in part of connecting means

whereby said plane has independent movement relative to the body of the aeroplane, and the angle of said plane is automatically varied by the action thereon of currents of air.

GEORGE E. MONTAGUE.
